United States Patent Office.

JOSEPH H. DAVIS, OF CHILlicothe, MISSOURI.

Letters Patent No. 92,519, dated July 13, 1869.

IMPROVED ADJUSTABLE BRACKET.

The Schedule referred to in these Letters Patent and making part of the same.

To all whom it may concern:

Be it known that I, JOSEPH H. DAVIS, of Chillicothe, Livingston county, Missouri, have invented a new and improved Adjustable Bracket; and I do hereby declare that the following is a full, clear, and exact description thereof, which will enable others skilled in the art to make and use the same, reference being had to the accompanying drawings, forming part of this specification, in which—

Figure 1 represents a front view of my improved adjustable bracket.

Figure 2 is a vertical transverse section of the same, taken on the plane of the line x x , fig. 1.

Figure 3 is a horizontal section of the same, taken on the plane of the line y y , fig. 2.

Similar letters of reference indicate corresponding parts.

This invention relates to a new clock-bracket, which is so arranged that it can be readily attached to the wall without marring the same, and that it can also be readily removed and adjusted to bring its surface on a level.

A, in the drawing, represents the body of the bracket, of which a is the top plate, b , the back plate, and c are the side trusses.

B is a metal plate or bar, fastened to the wall by means of screws d , or otherwise.

From its lower part projects a screw, C, through a segmental slot, e , of the back plate b , while a notched pin, f , projects from the plate B, through the upper part of the back plate b .

To the back plate is pivoted a cam, g , with a spiral edge, so that it can be turned to fit into one of the notches of the pin f , thus holding the upper part of the bracket close to or a suitable distance away from the plate B.

A nut, h , is fitted upon the screw C, a suspended

slotted plate, i , being interposed between it and the plate b .

Cams j are pivoted to the sides of the braces c , near the lower end of the bracket, and other cams, k , to the under side of the top plate a , all of these cams fitting through the back plate, as shown in fig. 3.

This bracket can be readily adjusted on the wall to be level.

By means of the cams j the upper, and by the cams k the lower, part of it can be thrown and held more or less forward, to bring the back plate into the required plumb position.

The segmental slots e permit the whole device to be swung on the pin f , to adjust the top plate to the proper level.

A drawer, D, running on guides l , may be arranged on the under side of the top plate, and can be provided with a suitable catch, m , whereby it is locked.

A weighted cam, n , to indicate the plumb position of the back plate, may be suspended from the top, as shown.

Having thus described my invention,

I claim as new, and desire to secure by Letters Patent—

1. An adjustable bracket, A, pivoted to the strip B, so that it can be transversely and longitudinally adjusted, substantially as herein shown and described.

2. The combination of the bracket A, cam g , and cams j k with the strip B, screw C, notched pin F , and nut h , all combined and operating substantially as herein shown and described.

The above specification of my invention, signed by me this 8th day of March, 1869.

JOSEPH H. DAVIS.
